FEEDING DEVICE FOR THE CARRIAGE OF
LATHES AND TURRET LATHES

Walter Möbius, Bielefeld, Germany, assignor to Werkzeugmaschinenfabrik Gildemeister & Comp., Akt.-Ges., Bielefeld, Germany

Application May 1, 1951, Serial No. 227,363

Claims priority, application Germany May 2, 1950

6 Claims. (Cl. 82—22)

The feeding device for the carriage of lathes and turret lathes is often equipped with an adjusting device controlled by hand which serves simultaneously for the throwing into gear and out of gear of the automatic feed device. But the known constructions of these engaging means have the disadvantage that the throwing into gear of the automatic feed device is difficult if the tooth system, serving as a clutch for the driving member, does not make contact instantly.

Another disadvantage of the known feeding devices is the necessity to move the hand wheel or the hand lever toward the lathe for throwing into gear the automatic feed device. Hence an unintentional engaging may occur, if the workman leans against the hand lever.

The development of the hand wheel control according to the invention removes these disadvantages.

A main feature of the invention is the connection of the hand wheel and particularly of the hand levers with a drop worm which is driven by the shaft of the feeding device instead of the toothed gear used hitherto. That drop worm will be engaged to a worm gear located on the axis of the hand wheel or the hand levers, if that control part is moved in the direction away from the lathe. That arrangement guarantees a throwing into gear of the automatic feed device instantly and without difficulties. An unintentional engaging of these parts cannot occur because the hand lever must always be moved in the direction away from the lathe, if the automatic feed devices shall be engaged.

Another advantage is the possibility to disengage the automatic feed device by an adjustable block on the carriage.

An example of the invention is shown on the drawings. Fig. 1 is a section through the manual engaging device;

Fig. 2 is a section through the lower part of the device to line E—E of Fig. 1;

Fig. 3 is a detail;

Fig. 4 is another section through the manual engaging device; and

Fig. 5 is a detail.

The hollow axis 2 is rotating in the casing 1 and carries on its end directed towards the lathe a pinion 4 which engages the gear rack of the carriage (not shown in the drawings). A hub 5 is located on the other end of the axis which carries inside the casing a worm gear 3. The driving shaft 7 for the automatic feed device is rotating in bearings on the casing 1 below the hollow axis 2. A drop worm 9 is driven by the shaft 7 by means of pinions 8. The axis 10 of the drop worm 9 is located in arms 11 which are swinging around the shaft 7 to throw the drop worm in and out of gear with the worm gear 3.

The up or down movement of the drop worm 9 is exerted by the moving of the hand levers 6. Several of these levers, mostly four, are located in the hub 5 and they form together the hand wheel which is used for the hand feeding mechanism. The hand levers 6 are fixed in holders 12 which are turnable around the bolts 13 located with their axis transverse to axis 2. Therefore the holders can be moved in planes parallel and radial to the axis 2. The hand levers 6 have on their inner ends thumbs 14 which engage into the annular groove 15 of a disc 16, fixed on the end of a sliding bar 17 located in the hollow axis 2.

A disc ring 19 is sliding on the axis 2 under the influence of a pressure spring 18; the hub 19' of the disc ring 19 carries a wedge 21 which is movable in the longitudinal

2

slots 20 of the hollow axis 2; the wedge is moreover connected with the sliding bar 17.

Thereby the disc ring 19 is joined with the hand levers 6 and both parts must be moved together.

One of the arms 11 is provided with a thumb 22 laying against the disc ring 19 and on the other hand with a nose 23 engaging a recess 24 of the blocking lever 25 movable on the axis 26. Thereby the drop worm 9 remains in contact with the worm gear 3 by blocking the arms 11 in their uppermost position.

The blocking lever 25 has a plug 27 which contacts a disc 29 in an annular recess 28 of the worm gear 9. Stay bolts 30 are fixed in the disc 29, and the stay bolts reach through bored holes in the worm gear 3 contacting the disc ring 19. The stay bolts 30 are surrounded by pressure springs 31 to ensure that contact.

The drop worm 9 is located in its out position on the floor of the casing 1 and it is held there by a tension spring 32 which is fixed on the arm 11. That is the position in which the feed can be exerted by hand by turning the hand wheel. If a change to the automatic feed shall take place, then one of the levers 6 must be turned in the direction of the arrow C (Fig. 1), to move the disc ring 19 against the pressure spring 18. By that displacement thumb 22 and the arms 11 are moved in the direction of the arrow D, so that the nose 23 engages the recess 24 in the blocking lever 25. In that moment the drop worm 9 engages and drives the worm gear 3. That position is locked by the extension spring 34 on the lever 33 which is turnable around the bolt 26 of the blocking lever 25, as it is shown in Fig. 4. The other end of the extension spring 34 is fixed on the bolt 36.

The disengaging of the automatic feed device is exerted by hand by turning the hand lever 6 contrary to the direction of the arrow C (Fig. 1), so that the disc ring 19 is moved in the direction of the gear wheel 3. The stay bolts 30 follow that movement and therefore the blocking lever 25 releases the nose 23 and the drop worm falls down to the bottom. That retract is aided by the tension spring 32.

The disengaging of the automatic feed device of the carriage can also be exerted by a block adjustably mounted on the lathe bed in a usual way. For that purpose the two-armed lever 35 is turnable around the bolt 36. One arm of the lever 35 has an inclined gliding surface 37 attached to the roll 38 on the free end of the lever 33, as it is shown in Figs. 4 and 5. The other end of the lever 35 is formed to a fork 39 which embraces the block 42, adjustable on the rod 40 under the pressure of a spring 41.

If the carriage strikes the block on the lathe bed, then the block 42 is moved contrary to the tension of the spring 41, so that the two-armed lever 35 is turned, thereby the gliding surface 37 gives free the roll 38, the lever 33 is turned and therefore the nose 23 is disengaged. The nose 23 lets fall the drop worm 9 and the worm gear 3 is stopped.

The pressure springs 18 and 31 effect in contrary directions, so that their pressure can be regulated to bring the lever 6 after the termination of the control movement to a middle position.

The hand levers 6 are fixed in the holders 12 by clamping screws 43. The levers 6 can be taken out of their holders by loosening the clamping screws, which is expedient for the transport of the machine.

The hub 5 and the holders 12 are secured by a cap 44, which is held in its position by screws or wire snaps. The bottom of the casing 1 is formed as an oiling bath into which the drop worm immerses, to secure a good lubrication of the gear.

Having thus described the invention, what I claim as new and desire to be secured by Letters Patent, is as follows:

1. In a feeding device for the carriage of lathes and 75 turret lathes provided with means for hand feed and power feed, a casing fixed on said lathe, a driving shaft journaled in said casing, a drop worm operatively connected to said driving shaft, arms turnable on said driving shaft and carrying said drop worm, a hollow shaft journaled in said casing, a pinion fixed at the free end 80 of said hollow shaft to drive said carriage, the axis of said

hollow shaft being directed vertically to the axis of said driving shaft, a worm gear fixed on said hollow shaft, a bar slidingly located inside of said hollow shaft, at least one hand lever connected with said slide bar and with said hollow shaft and means operatively connected to said slide bar and to said turnable arms to disengage said drop worm from said worm gear by a movement of said hand lever in the direction towards the lathe.

2. In a feeding device according to claim 1, a hub fastened to said casing, a holder embracing said hand lever, a bolt fixed in said holder and journaled in said hub, the axis of said bolt extending vertically to said hollow shaft, a disc ring slidably located on said hollow shaft and being connected to said slide bar, a nose fastened on said turnable arms, a blocking lever for said nose operatively connected with said disc ring to transmit the movement of said hand lever to said blocking lever.

3. In a feeding device according to claim 2, longitudinal slots in said hollow shaft, a wedge movable in said slots and being connected with said slide bar and said disc ring, a spring located on said hollow shaft and adapted to be pressed against said disc ring, displaceable stay bolts carried by said worm gear and being in contact with said disc ring, a recess in said worm gear, an annular disc located in said recess and being in contact with said stay bolts, said blocking lever being in contact with said annular disc, a recess in said blocking lever to support said nose in the engaging position of said drop worm with said worm gear.

4. In a feeding device according to claim 2, a thumb fixed on said turnable arms and being in contact with said disc ring, a draw spring connected with said turnable

arms and said casing to withdraw said drop worm after the disengagement of said nose by rotating said blocking lever.

5. In a feeding device according to claim 3, springs surrounding said stay bolts to produce a contact of said stay bolts with said disc ring, the pressing force of said springs being equal to the force of the spring surrounding said disc ring to stop said hand lever in its middle position.

6. In a feeding device according to claim 1, a lever connected with said blocking lever, a roll attached to the free end of said lever, a two-armed lever rotatably journaled in said casing and having a gliding surface contacting said roll, an adjustable block provided on the other arm of said two-armed lever, a spring contacting said block and being located in the way of said carriage to disengage automatically the blocking position of said drop worm with said worm gear.
